UNITED STATES PATENT OFFICE.

SIMEON B. KIRTLEY, OF COLUMBIA, MISSOURI.

VISIBLE-ACCOUNT LEDGER.

1,291,925.

Specification of Letters Patent.

Patented Jan. 21, 1919.

Application filed December 26, 1916. Serial No. 138,858.

To all whom it may concern:

Be it known that I, SIMEON B. KIRTLEY, a citizen of the United States, residing at the city of Columbia, county of Boone, and

5 State of Missouri, have invented a new and useful Visible-Account Ledger, of which the following is a specification.

This invention relates to visible account ledgers.

10 An object of the invention is to provide a ledger embodying series of master sheets each adapted to contain the record of an account or accounts and each provided with a visible index serving also as a master 15 index for any desired number of sub-divisions of sheets adapted to have entered thereon sub-indexes of accounts having a predetermined relation to the master index, and all of the sheets being arranged so that 20 when the ledger is opened at any sub-division of any master index, the master index and the sub-indexes of that sub-division are visible.

Another object is to provide a visible 25 account ledger embodying series of visibly indexed master sheets, selected ones of which serve as master indexes for adjacent series of sheets arranged in sub-divisions and each provided with a visible space adapted to 30 have entered thereon a sub-index of the account contained thereon, and each of the sub-division sheets containing, adjacent to the sub-index, a space for the name in which the account is entered.

35 A further object of the invention is to provide a visible account ledger embodying the features of construction and arrangement mentioned, in combination with tabs attached to division sheets interposed between each group composed of the master sheets and the related sub-division sheets, whereby the number of tabs required for locating the accounts rapidly and with facility is very greatly reduced, it having 40 been determined from experience that such construction dispenses with the use of approximately three-fourths, more or less, of the index tabs required in connection with ledgers heretofore in use.

45 Other objects of the invention will appear from the following description, reference being made to the accompanying drawings, in which—

50 Figure 1 is a perspective view of a ledger embodying my invention.

Fig. 2 is a detailed view illustrating the relation of the master index to the sheets in the sub-division related thereto.

Fig. 3 is a detailed view illustrating a number of the master indexes and a series of sub-division sheets related to one of the master index sheets in proper position in relation thereto, and another sub-division sheet below its proper place in order to show that the latter sub-division sheet will cover 60 all of the sub-division sheets of the first-named series when in its proper place. 65

The ledger illustrated is of the loose-leaf type comprising binding mechanism 1 of known construction for binding the leaves 70 together in book form, and covers 2 hinged to the binding mechanism. It is well known that loose-leaf binders of this construction are adjustable to receive varying numbers of sheets, so that largely varying numbers 75 of master index sheets and sub-divisions may be bound within the same volume. However, I do not confine myself to use of my invention in books or binders of any specific type, since it will be readily apparent from 80 the following description that the invention may be applied to books of other forms.

The sheets in each book are divided 85 alphabetically and a selected number of sheets are assigned to each individual letter. The number of sheets assigned to each letter varies in proportion to the frequency of its occurrence as the initial letter of surnames, as determined or ascertained by experience 90 and observation, or individual requirements in any instance. Also, in cases in which any letter is used so frequently as the initial letter that it is rendered impracticable to place in one series all of the master indexes 95 in visible relation at the top of the sheets as hereinafter explained, such letter may be provided with any desired number of series of master index sheets.

Referring now to the particular construction illustrated in Fig. 1, the ledger is open before the division sheet belonging to the series of master index sheets assigned to the letter A. For this letter there is provided a division sheet 3 having at its marginal edge a lettered tab 4. It will be understood 100 that each index letter is also provided with a sub-division sheet and that in cases where the frequency of use of any letter as an initial letter of a surname requires the provision of two or more series of master in- 105 110

dex sheets, there will be a tab for each series. For instance, it will be observed that there is a tab 5 containing the letters BA and another tab 6 containing the letters BL. In 5 this case I have learned from experience that there are so many surnames beginning with the letter B and followed by another letter of the alphabet prior to L, that a complete series of master index sheets is required 10 therefor. This necessitates the provision of another series of master index sheets for the initial letter B of the surname, when such letter is followed by L, or some other subsequent letter of the alphabet. It will be 15 observed that this arrangement is also followed in the book illustrated for other letters, as for instance, the letters C, H, M, S and W. Of course, the number of tabs will be increased or decreased in proportion to 20 the number of accounts to be entered.

It is preferable that the upper portion of the division sheet 3 be cut away to uncover all of the master index sheets under it, and this is true also of the division sheets in the 25 ledger. As illustrated in Fig. 1, there is a series of master index sheets 7 for the initial letter A, and for the purpose of illustration I have shown the initial letter A upon seven master sheets. The seven master indexes illustrated in Fig. 1 for purposes of explanation include the letters Ac, Ad, Al, Am, An, Ar and Ay, but obviously, the number of master sheets may be varied as required. These master indexes are rendered visible 30 by cutting away the upper right hand corner of the master sheets in stepped series, it being understood that as many sub-index sheets as desired, or as necessity may require, are placed in front of each master sheet. 35 The division sheet 3 contains, adjacent to its upper marginal edge, a series of indexes 8 corresponding to and in alinement with all of the master indexes on the master sheets. For each master index 8 contained 40 upon the division sheet there are in alinement therewith as many sub-indexes 9 as there are sub-indexes in the series of sub-division sheets belonging to each master sheet. Thus, names beginning with Aa and 45 Ab are indexed in front of the master index Ac, and the accounts of these names are carried upon the sub-division sheets in front of the master index Ac.

Since the letter C immediately precedes 50 the letter D in the alphabet, no sub-indexes for the master index Ad are required, but there are a number of sub-indexes between the master index Ad and the index Al. These sub-indexes, as shown, comprise several of the first letters of surnames beginning with Ae, Af, Ag, Ah, Ai, Aj and Ak, it being obvious that other letters in addition to the first two letters may be added to distinguish the different names from each 55 other; as for instance, the sub-index Ailw

may be used to distinguish the name "Ailworth" from the sub-index Aitk for the name "Aitken." Since the letter M immediately follows the letter L in the alphabet no sub-indexes for the master index Am are 70 necessary, and, for like reason, no sub-indexes are shown for the master index An, but there are illustrated sub-indexes for the master indexes Ar and Ay.

In the embodiment illustrated in Fig. 1, 75 indexes corresponding to the indexes 8 are duplicated in vertical alinement, as shown at 10 near the middle of the page, and sub-indexes corresponding to the sub-indexes 9 are placed in alinement therewith as shown 80 at 11. It will be understood, however, that either one of these forms may be employed, as preferred, and in this particular I do not confine myself to any specific arrangement.

In Fig. 2 a series of sub-index sheets are 85 illustrated placed before the master index sheet having the master index An. The first sub-index sheet 12 is cut away two steps or spaces from the cut away edge of the master index AN, thus providing a visible space 13 90 on the master index sheet AN in which may be entered a sub-index consisting of a number of the first letters of the surname of the account entered on that page. Also, the visible portion of each of the sub-index sheets 95 in the series has a visible space in which may be entered sub-indexes as shown in Fig. 2, so that these sub-indexes are governed by the master index to which they belong.

It is preferable also that certain of the 100 sub-index sheets be arranged so that they may be cut away at the right hand edge and below the upper cut away portions to provide visible sub-index spaces below the master indexes. This will be understood by 105 reference to Fig. 2 in which the sheet containing the account of "C. T. Anderson" is cut away, as shown at 14 to disclose a series of second sub-index sheets, and the sub-index "C. T." has been entered upon this sheet as shown at 15. Thus, when the sub-index sheets in a series are so numerous that the additional cut away spaces are required to make the sub-indexes visible, this may be effected as shown in connection with the 110 sheet containing the account of "C. T. Anderson". This arrangement is followed only in cases in which the sub-indexes are 115 governed by the governing master index.

In other cases the arrangement is that 120 illustrated in Fig. 3. Thus, adjacent to the master index AD a sub-index ADA has been entered which will govern a number of accounts having names beginning with the letters ADA. However, accounts for such 125 names as "Addison" are not governed by the sub-index ADA, so that the additional sub-index sheet 16 is required. The additional sheet 16, when placed in the ledger, covers the sub-index sheets governed by the sub- 130

index ADA and discloses another sub-index, such as ADD. It will be understood that this arrangement is followed wherever required.

5 Each master index sheet, and each sub-index sheet is provided with a series of identifying characters 17, corresponding to the cut away portions thereof, to distinguish the sheets from each other; and the division sheet 3 is provided with a similar corresponding series of identifying characters 18 to identify the master indexes contained on the sheet. The identifying characters 18 by corresponding with the identifying characters 17 indicate to which of the master index sheets the various sub-indexes correspond.

From the foregoing it will be understood that my improved ledger embodies series of 20 master sheets for accounts and that each master sheet is provided with a permanently affixed visible index which serves also as a master index for any desired number of sub-divisions of sheets adapted to 25 have entered thereon the sub-indexes of accounts having a definite relation to and governed by the master index. It will be also understood that when the ledger is opened at any division sheet, all of the master indexes for that division are visible; and that when the ledger is opened above any series of sub-division sheets governed by any master index, the master index and all of the sub-indexes of that sub-division are also 35 visible.

It will also be understood that another feature of the invention consists in providing the sub-index sheets with visible spaces at their cut away edges adapted to have 40 entered thereon the sub-indexes of the accounts.

Another feature of the invention consists in the provision of the sub-indexes upon the division sheets in convenient relation to the 45 master indexes and adapted to be entered as sub-indexes upon the sub-index sheets governed by the respective master indexes.

The foregoing novel features of construction and arrangement may be varied and I 50 do not restrict myself to the specific arrangement and construction shown and described.

What I claim and desire to secure by Letters Patent, is:—

55 1. A book, having series of master index sheets cut away in stepped relation to form a visible space upon each sheet of the series, a master index permanently affixed upon the visible space of each sheet, a space upon each sheet adjacent to the master index adapted to have entered therein a sub-index 60 governed by the master index, a series of sub-index sheets before certain of the master index sheets and cut away in stepped relation to provide visible spaces adapted

to have entered therein sub-indexes having relation to and governed by the master index upon which they are directly superimposed, and to render visible the subsequent master indexes of the series, a division sheet 70 before each series of master index sheets having the master indexes thereon corresponding to all of the master indexes of the series, and a series of sub-indexes on the division sheet adapted to be entered on said 75 sub-index sheets.

2. A book, having series of sheets cut away in stepped relation to form a visible space upon the respective sheets of the series, a master index permanently affixed 80 upon the visible space of each sheet, a primary series of sub-index sheets before certain of the master index sheets also cut away in stepped relation so that the subsequent master indexes of that series are visible and 85 to provide visible spaces on the respective primary sub-index sheets adapted to have entered therein sub-indexes governed by the next adjacent master index, a second series of sub-index sheets cut away so that the 90 master indexes and the primary sub-indexes are visible, and also cut away in stepped relation to provide visible spaces adapted to have entered therein sub-indexes governed by the next adjacent master index, a division 95 sheet before each series of master index sheets having the master indexes thereon corresponding to all of the master indexes of the series, and a series of sub-indexes on the division sheet adapted to be entered on said 100 sub-index sheets.

3. A book, having series of master index sheets cut away in stepped relation to form a visible space upon the respective sheets of each series, a master index permanently 105 affixed upon the visible space of each sheet, identifying characters thereon to distinguish said master index sheets from each other, a series of sub-index sheets for certain of the master index sheets cut away in stepped relation to provide visible spaces adapted to have entered therein sub-indexes governed by the next adjacent master index, identifying characters on the sub-index sheets to distinguish them from each other, a division 110 sheet for each series of master index sheets, identifying characters on the division sheet corresponding to the identifying characters on the master index sheets and on the sub-index sheets, and sub-indexes upon the division sheet governed by certain of the master indexes of the series to which the master indexes respectively belong.

4. A book, having a series of master index sheets cut away in stepped relation to form 125 a visible space upon each sheet of the series, a master index permanently affixed upon the visible space of each sheet, a space upon each sheet adapted to have entered therein a sub-index governed by the master index, a first 130

series of sub-index sheets before certain of said master index sheets cut away in stepped relation to expose the succeeding master indexes and the sub-index on the first adjacent 5 master index sheet and to form a visible space on each sub-index sheet adapted to have entered therein a sub-index governed by the master index and also by the sub-index on the adjacent master index sheet, an 10 additional series of sub-index sheets before the first series of sub-index sheets cut away in stepped relation to expose the succeeding master indexes and also to expose the sub-indexes on the first adjacent master index 15 sheet and arranged to cover all of the sub-indexes on the first series of sub-index sheets, and to form a visible space on each of said second series of sub-index sheets adapted to have entered therein a sub-index governed 20 by the master index on the first adjacent master index sheet.

5. A book, having series of master index sheets cut away in stepped relation to form a visible space on each sheet of the series, a 25 master index permanently affixed upon the visible space of each sheet, identifying characters on said sheets corresponding to the cut away portions thereof respectively, a division sheet before each series of master 30 index sheets having the same master indexes thereon that are on the master index sheets to which said division sheets belong, identifying characters on the division sheet corresponding to the identifying characters on 35 the master index sheets and identifying the master indexes on the division sheet that correspond to the master indexes on the master index sheets respectively, and a series of 40 sub-indexes on the division sheet for the accounts adapted to be entered on said master index sheets.

6. A book, having series of master index sheets cut away in stepped relation to form a visible space upon each sheet of the series, a 45 master index permanently affixed upon the visible space of each sheet, a division sheet before each series of master index sheets having the same master indexes thereon that are on the master index sheets to which the 50 division sheet belongs, a series of sub-indexes on the division sheet for the accounts governed by the master indexes respectively, and account sheets before certain of the 55 master index sheets adapted to have entered thereon the accounts of the sub-indexes governed by the master indexes respectively.

7. A book having series of master index sheets cut away in stepped relation to form a visible space on each sheet of the series, an identifying character upon each of the master index sheets distinguishing the sheets from each other, a master index permanently affixed upon the visible space of each sheet, a division sheet before each series of master index sheets, and a series of sub-indexes on 60 the division sheet for the accounts adapted to be entered on said master index sheets.

8. A book having series of master index sheets cut away in stepped relation to form a visible space on each sheet of the series, 70 master index sheets distinguishing the sheets from each other, a master index permanently affixed upon the visible space of each sheet, a division sheet before each series of master index sheets, a series of sub-indexes on the 75 division sheet for the accounts adapted to be entered on said master index sheets, and identifying characters on the division sheets indicating to which of the master index sheets the various sub-indexes on the division 80 sheets correspond.

9. A book having series of master index sheets, an identifying character upon each of the master index sheets distinguishing the sheets from each other, a master index 85 permanently affixed upon each of said sheets adjacent to one of the marginal edges thereof, a division sheet before each series of master index sheets, and a series of sub-indexes on the division sheets for the matter adapted 90 to be entered on said master index sheets, said sub-indexes being governed by the master indexes on the master index sheets.

10. A book having series of master index sheets, an identifying character upon each 95 of the master index sheets distinguishing the sheets from each other, a master index permanently affixed upon each of said sheets adjacent to one of the marginal edges thereof, a division sheet before each series of master index sheets, a series of sub-indexes on the 100 division sheets for the matter adapted to be entered in said master index sheets, said sub-indexes being governed by the master indexes on the master index sheets, and identifying characters on the division sheets indicating to which of the master index sheets the various sub-indexes on the division 105 sheets correspond.

In witness whereof, I have signed this 110 specification.

SIMEON B. KIRTLLEY.
